(57) CLAIM

The ornamental design for a therapeutic bonding mitt as shown and described.

DESCRIPTION

FIG. 1 is a perspective view of an embodiment of a therapeutic bonding mitt;

FIG. 2 is a side view of a first side of the therapeutic bonding mitt of FIG. 1;

FIG. 3 is a side view of a second side of the therapeutic bonding mitt of FIG. 1;

FIG. 4 is a side view of a third side of the therapeutic bonding mitt of FIG. 1;

FIG. 5 is a side view of a fourth side of the therapeutic bonding mitt of FIG. 1;

FIG. 6 is a top view of the therapeutic bonding mitt of FIG. 1; and

FIG. 7 is a bottom view of the therapeutic bonding mitt of FIG. 1.

FIG. 8 is a perspective view of a second embodiment of the therapeutic bonding mitt;

FIG. 9 is a side view of a first side of the therapeutic bonding mitt of FIG. 8;

FIG. 10 is a side view of a second side of the therapeutic bonding mitt of FIG. 8;

FIG. 11 is a side view of a third side of the therapeutic bonding mitt of FIG. 8;

FIG. 12 is a side view of a fourth side of the therapeutic bonding mitt of FIG. 8;

FIG. 13 is a top view of the therapeutic bonding mitt of FIG. 8; and,

FIG. 14 is a bottom view of the therapeutic bonding mitt of FIG. 8.

The broken lines in the drawings illustrate portions of the therapeutic bonding mitt which form no part of the claimed design.

1 Claim, 14 Drawing Sheets

Related U.S. Application Data

continuation of application No. 17/185,982, filed on Feb. 26, 2021, now Pat. No. 12,035,688.
